UNITED STATES PATENT OFFICE.

ARETAS S. McCLEARY, OF KANSAS CITY, MISSOURI.

RECTAL PLUG.

1,244,751.

Specification of Letters Patent. Patented Oct. 30, 1917.

Application filed October 16, 1916. Serial No. 125,950.

To all whom it may concern:

Be it known that I, ARETAS S. McCLEARY, a citizen of the United States, residing at Kansas City, in the county of Jackson and 5 State of Missouri, have invented certain new and useful Improvements in Rectal Plugs, of which the following is a specification.

My invention relates to improvements in adjustable rectal plugs, and one object is to 10 provide a simple, inexpensive, and efficient instrument of this character which may be employed to advantage in the treatment of rectal diseases.

While the instrument can be used to advantage in the treatment of various kinds 15 of rectal troubles, it is especially efficient in checking hemorrhages due to surgical operations, by exerting pressure on the walls of the rectum until the flow is stopped.

Other objects and advantages will herein- 20 after appear, and in order that the invention may be fully understood, reference will now be made to the accompanying drawing, in which:

Figure 1 is a side elevation of the device contracted to its smallest diameter.

Fig. 2 is a vertical, central section of the device partly expanded.

Fig. 3 is a cross section on line III—III 25 of Fig. 2.

In carrying out the invention, I employ a plurality of curved fingers 1 adapted to fold against each other as disclosed by Fig. 1, or be spread apart as disclosed by Fig. 35 2. Each finger 1 is pivotally-mounted at one end in a bearing 2, which is fixed within the socket of a retaining member 3 having a handle 4.

5 designates an internally-threaded tube 40 fixed centrally in the handle 4 and the bearing 2, beyond which latter it extends a suitable distance as disclosed by Fig. 2.

6 designates a plunger for expanding or 45 spreading the fingers 1 apart. Said plunger comprises a threaded stem 8 and a disk 9, which latter is swiveled upon one end of the former, so that when the plunger stem is rotated the disk 9 need not rotate therewith and thus wear the contacting surfaces of 50 the fingers 1 more or less. In order that the plunger 6 may readily spread the fingers 1 apart, the latter have inner inclined surfaces 11 for contact with the disk 9, so that when the same is adjusted toward the 55 adjacent end of the tube 5 it will spread the

fingers apart more and more as it approaches said tube.

The plunger 6 is adjusted up and down by means of a detachable key 12, having a slotted terminal 13 for engagement over a pin 60 14 extending transversely through a socket 15 in the outer end of the plunger stem 8.

In practice the fingers 1 are folded to their most compact form, as disclosed by Fig. 1, so that they can be readily inserted 65 in the rectum, after which they are spread apart to exert pressure on the walls of the rectum by turning the key 12 in the proper direction to cause the plunger to move downward along the inclined surfaces 11. In 70 case of a hemorrhage the pressure on the walls of the rectum is sufficient to check the flow which is permitted to escape through the spaces between the fingers 1 until checked. In some instances it is desirable 75 to cover the fingers with a rubber or cloth to act as a dam and exert pressure against those portions of the rectum walls which the fingers themselves do not contact.

Upward movement of the plunger 8 is 80 limited by the end of the socket 15 contacting the handle 4, and downward movement of said plunger is limited by the disk 9 contacting the adjacent end of the tube 5.

From the foregoing description, it is apparent that I have produced an instrument possessing all of the advantages above enumerated, and while I have shown and described the preferred form of my invention, I reserve the right to make such 90 changes in the construction, combination, and arrangement of parts as properly fall within the spirit and scope of the claims.

Having thus described my invention, what I claim and desire to secure by Letters 95 Patent, is:

1. In a rectal plug, a retaining member having a socket and provided with a handle, a bearing member in the socket, fingers pivoted in the bearing, an internally threaded tube extending through said socket, a plunger threaded in the tube, means on the inner end of the plunger to spread the fingers and being engageable with the inner end of the tube to limit the out movement 100 of the plunger, a socket on the outer end of the plunger, a pin extending across the socket, and a removable key receivable in the socket and having a slotted terminal receiving the pin, said socket being engageable 105 110

with the handle to limit the in movement of the plunger.

2. In a rectal plug, a handle, an internally threaded tube rigidly connected at one end with the handle, fingers pivoted about the tube, a plunger threaded in the tube, means on the inner end of the plunger to spread the fingers and being engageable with the inner end of the tube to limit the out movement of the plunger, a removable key for the plunger, and means on the plunger to

connect the key thereto so as to enable the key to rotate the plunger, said plunger means being engageable with the handle to limit the in movement of the plunger. 15

In testimony whereof I affix my signature, in the presence of two witnesses.

ARETAS S. McCLEARY.
